CLOCKING MECHANISM FOR KNITTING-MACHINES.

1,198,275.

Specification of Letters Patent. Patented Sept. 12, 1916.

Application filed December 1, 1915. Serial No. 64,550.

To all whom it may concern:

Be it known that we, EDWARD RICK and WILLIAM G. STOLZ, citizens of the United States, and residents of Reading, county of Berks, and State of Pennsylvania, have invented a certain new and useful Improvement in Clocking Mechanisms for Knitting Machines, and do hereby declare that the following is a full, clear, and exact description thereof.

Our invention relates to knitting machines, and more particularly to that type of knitting machine wherein extra, or additional thread forming the body of the article is used, as for example, in hosiery, and the object of our invention is, generally stated, to provide a knitting machine for supplying such additional thread which will have the important advantages of simplicity of parts to the end that the first cost of manufacture may not be great and the likelihood of derangement eliminated; readiness, or ease of adjustment, so as to vary the extent of the application of the extra thread over the body of the article being knitted; and ease and quickness of access to the knitting mechanism which requires the removal, or displacement from position of the extra thread mechanism, and with this object in view, and to secure advantages which will be apparent to those skilled in the art when the embodiment of our invention is understood from the following description, our invention consists in the knitting machine having the characteristics of construction substantially as hereinafter specified and claimed, and one embodiment of which invention is shown in the accompanying drawings in which—

Figure 1 is a view partly in side elevation and partly in section of such embodiment of our invention; Fig. 2 is a top plan view partly in horizontal section; Fig. 3 is a section on the line 3—3 of Fig. 2; Fig. 4 is a detail view in side elevation of the extra thread carrier actuating means; Fig. 5 is a detail view of the pawl and ratchet actuating device of said thread carrier; Fig. 6 is a side elevation of the rack bar raising lever; Fig. 7 is a detail view on an enlarged scale of the lower portion of the extra thread carrier; Fig. 8 is a horizontal

section on the line 8—8 of Fig. 1; Fig. 9 is a detail view in perspective of one of the extra thread carrier levers.

The machine shown in the drawings in which our invention is embodied, is a circular knitting machine of the well known construction for knitting stockings, having a needle cylinder 10, needles 11 and the rotatable cam ring 12 for vertically reciprocating the needles. As is common in this art the extra thread carrier for forming the clock in the case of a stocking machine, is caused to place, or carry such thread around the desired number of needles, according to the design to be made, and one, or more of such carriers may be employed. In the machine shown in the drawings there are two such carriers, and as the construction of the carrier mechanism itself is alike in all that are employed, it will be understood that the description of one carrier mechanism will apply to all.

The extra thread carrier 13 is a vertically extending lever that depends from and is carried by a crank device of variable throw hereinafter described, that is mounted on a head 15 which is supported above and slightly eccentric to the circular row of needles and cam ring, for in the case shown, the clocks are slightly to one side of the center of the stocking. The head 15 is secured, as by means of a set screw 16 to the lower end of a non-rotary vertical shaft 17, and which at its upper end passes through and fits an opening in an arm 18 of a column, or upright 19 that is supported by and rises from the base of the machine, the shaft 17 having, above and below the portion of the arm 18 through which it passes, collars 20 and 21, respectively. Closely fitting between the lower set collar 21 and the arm 18 above it, is a horizontally extending bar, or yoke 22, which is adapted to rotate about the shaft 17. It will thus be seen that by the two set collars and the portion of the yoke above the lower set collar 21, the shaft 17 is supported vertically immovable. The yoke 22 at its diametrically opposite outer ends has fixed to it the upper end of two vertical diametrically opposite rods 23 which at their lower ends are, respectively, connected to diametrically projecting radial

arms 24 on the cam ring by the rotation of which the rods 23 are revolved in a path, or orbit concentric with the shaft 17, the purpose of which, as hereinafter explained, 5 is to impart the rotary movement to the additional thread carrier to pass the additional thread about the needles of the knitting machine for clocking the stocking being knitted.

10 The variable throw crank mechanism comprises a tubular shaft or sleeve 25, journaled in a vertical hole in the arm 15, and a head 26 at its lower end on the under side of said arm 15, which head has a diametrically extending slot or groove 27. In the latter is slidably fitted a horizontal block 28, from the bottom of which projects downwardly a shank 29, that is bored vertically with a round hole 30, in which is fitted the round 15 stem 31 that constitutes the upper portion of the thread carrier 13. The stem 31 has near its lower end an annular flange or collar 32, and screwed on the lower end of the shank 29 is a coupling collar 33, which 20 engages the lower side of the stem flange 31 connects the thread carrier with and supports it from, the slidable block and slotted head which constitute the crank device. It 25 will be evident that, when the vertical axis of the thread carrier is coincident with the vertical axis of the crank shaft 25, no orbital movement of the thread carrier can take place, but if the block 28 be shifted horizontally in the slot in the crank head, the 30 thread carrier will describe a circular path of a diameter agreeing with or determined by the extent of eccentricity of longitudinal axis of the thread carrier to the axis of the crank shaft 25. Normally, coincidence of 35 these two axes is maintained as by means of a coil spring 44, which at one end bears against an end wall of the head 26, and at the other end bears against the slidable block or crank pin 28. On the upper side of the latter is a downwardly and horizontally inclined cam face 34, which is engaged by the lower inclined end 35 of the vertically movable bolt 36, mounted in the tubular crank 40 shaft 25. It will be evident that by a downward movement of the bolt 36, forcing its lower inclined end against the cam face 34, the slidable crank pin will be moved bodily sidewise, and carry with it the thread carrier 13. Thus, with power applied to the 45 crank shaft 25, to rotate it, the thread carrier 13 will be caused to revolve in an orbital path of greater or less diameter, according to the degree of eccentricity which 50 is produced by the lateral shifting of the thread carrier 13.

For rotating the crank shaft 25, we provide a toothed wheel 40 upon the upper end thereof above the head 15, and a rack bar 41 which rests upon and is attached to a yoke plate 42 which extends between the two 55 rods 23, the rack bar, being, by the revolution of the rod 23 about the shaft 17, brought into an engagement with the wheel 40 and imparting a single revolution to the sleeve 37 to carry the additional thread about the 60 desired number of knitting needles.

The rack bar 41 is movable vertically so that when it is desired to prevent it acting upon the wheel 40 that can be done, a lifting lever 41^a being provided for that purpose 65 that has a cam slot 410 that engages a stud or pin 411 on a depending arm of the rack. The rack is latched in its raised and its lowered position by providing a pawl 412 in the form of a spring-pressed ball adapted 70 to seat in either of two depressions 413 in the side of the lever. The connection between the yoke 42 and the rack bar to permit this up and down movement of the rack bar consists of several vertical pins 420 that 75 project from the upper side of the yoke and which pass through holes in the rack bar.

The cam actuating bolt 36 at its upper end is reduced in diameter and projects free and in position to be engaged by a sleeve 45 80 vertically slidable upon the shaft 17, or by the adjustable pin, or screw 46 carried by said sleeve, so that by the downward movement of the sleeve 45 the bolt 36 will be moved downward against the upward pressure of a spring 45^a. The sleeve 45 serves as a bobbin carrier for the supply of the extra thread, said sleeve being provided with a radially projecting arm 450 for each 85 bobbin having the usual bobbin-receiving stud, or post 451.

Above the top of the sleeve 45, and resting thereon, is a block, or key 47 which passes diametrically through a slot 48 in the shaft 17, said slot being vertically elongated 90 so as to allow the desired vertical movement of the key 47 to impart movement to the sleeve 45, and said key on its top is engaged by the lower end of a rod 48 which extends through a central axial hole 50 in the shaft 95 100 105 110 115 120 125 130

17 and projects above the shaft, and upon its upper end has a head, or cap 51 slideable vertically upon the reduced upper end of the shaft. Above the head is a disk 52 upon the lower end of a vertical shaft 53 mounted to revolve on an axis eccentric to the axis of the shaft 17, said shaft 53 being journaled in and supported by a bearing 54 in the arm 18. The disk 52 is provided with a number of adjustable pins in the form of screws 55 which project below the lower side of the disk and which are of a number agreeing with the number of changes in needles to be wrapped, according to the design desired, and which one at a time by the rotation of the disk 52 are made to travel over the top of the head 51, which is cam-shaped, and thereby cause the descent of the head 51 and the rod 49, and through the various connections we have described, causing the down-

ward movement of the bolt 36 and the shifting of the thread carrier 13 to the desired position required by the number of needles to be wrapped. It will be seen that the 5 amount of projection of the pin 55 below the bottom of the disk 52, determines the angle to which a thread-carrying lever 13 shall be swung, and accordingly the number of 10 knitting machine needles about which the 15 additional thread will be wrapped.

For revolving the disk 52, its periphery is provided with, or formed into ratchet teeth 56, and a feed pawl or ratchet 57 is pivoted to the upper end of a lever 58 which is pivoted intermediate its ends to the side of the 15 upright, or post 19 and by a suitable connection with some rotating member of the knitting machine, is rocked at the proper time to cause the turning movement of the 20 disk 52.

The thread carrier 13 is jointed immediately below, or contiguous to its stem so that its portion below said stem is connected by a pivot pin 59 with the upper portion, the 25 pin 59 extending horizontally so that practically all of the finger below the collar 33 may be swung outward and upward and thus entirely away from the knitting needles. By this arrangement, when access to 30 the knitting needles, or to the stocking being knitted, as for the purpose of applying the top to the stocking, is required, all that is necessary to do is merely to swing the lower 35 eye-carrying member of the carrier finger 13 in the manner described without the disturbance of any other part of the mechanism. A holding device, such as a set screw 60, is provided to secure the lower portion 40 of the finger 13 in proper operative position. It is important to prevent rotation of the thread carrier 13 on its own longitudinal axis, for could it so rotate, the thread would be wound and tangled thereon. To prevent such rotation, but at the same time allow the 45 free bodily rotation of the carrier by the action of the crank mechanism, we attach to the lower end of the shaft 17 a radial finger 61 which slidably fits a radial hole 62 in the upper part of the block 63, to which the 50 lower portion of the carrier is hinged, and to which the carrier stem at its lower end is connected, as by the threaded connection shown. The radial finger 61 has a pivotal connection with the shaft 17, so that with the 55 slidable connection which it has with the carrier block 63, it permits the orbital revolution of the carrier when that is produced by the crank mechanism, while preventing revolution of the carrier on its axis. The 60 radial finger 61 is not a support for the thread carrier 13, but the latter is wholly supported or suspended by its connection with the crank shaft, through the medium of the slotted head 26 on the latter, said 65 head having on its under side near each end,

a cross bar or strap 64, upon which rests the crank pin block 28.

The carrier finger 13 has its lower portion formed of a slender shank 65 and the thread-guiding eye is formed by a longitudinally extending, axial hole 66 reaching from the lower end of said shank upward, and by a lateral cut 67 that intersects the upper portion of the hole 66.

It is to be remarked that we understand 75 that the scope of our invention extends to other constructions than appears in the embodiment shown in the drawing and described in detail in this specification, and the scope of our claims is to be understood 80 in the light of this statement.

Having thus described our invention what we claim is—

1. In a knitting machine, the combination 85 with the needles and the needle actuating mechanism, of additional-thread-supplying means comprising a thread carrier, means to cause the thread delivery point of the carrier to revolve about the needles, comprising a rotary member with whose axis of 90 rotation the longitudinal axis of the finger normally coincides, means to shift the thread carrier bodily, radially of the axis of the rotary member to vary the size of the orbital path described by its thread delivery 95 point.

2. In combination with needles of a knitting machine, additional thread-supplying means comprising a finger, means to cause 100 the thread delivery point of the finger to revolve about the needles, comprising a rotary member, and means to shift said finger bodily 105 radially of the rotary member to and from a point concentric therewith and to maintain said finger in the positions to which it may be shifted out of its concentric position, said revolving means acting to revolve the finger while in its shifted position.

3. In combination with the needles of a 110 knitting machine, additional thread supplying means comprising a finger, a variable throw crank, suspending said finger, so that at all times the longitudinal axis of the finger is either coincident with or parallel with the axis of revolution of the crank means for imparting rotation to the crank intermittently, and means for shifting the finger radially of the axis of revolution of the 115 crank.

4. In combination with the needles of a 120 knitting machine, additional thread supplying means comprising a finger, a variable throw crank, suspending said finger, so that at all times the longitudinal axis of the finger is either coincident with or parallel with the axis of revolution of the crank, means for imparting rotation to the crank intermittently, means for shifting the finger radially of the axis of revolution of the crank, 125

- and means to prevent rotation of the finger on its axis.
5. In a knitting machine, the combination with the needles and the needle actuating mechanism, of additional-thread supplying means comprising a thread carrier, means to cause the thread delivery point of the carrier to revolve about the needles, including a rotating member, shiftable means connecting the thread carrier therewith, and means for changing the point of such connection radially of the rotating member.
6. In a knitting machine, the combination with the needles and the needle actuating mechanism, of additional-thread supplying means comprising a thread carrier, means to cause the thread delivery point of the carrier to revolve about the needles, including a rotating member, and means to shift the position of the delivery point of the carrier from coincidence with the axis of rotation of said rotating member to a position eccentric thereto.
7. In a knitting machine, the combination with the needles and the needle actuating mechanism, of additional-thread supplying means comprising a thread carrier, means to cause the thread delivery point of the carrier to revolve about the needles, including a rotating member, and means to shift the position of the delivery point of the carrier from coincidence with the axis of rotation of said rotating member to a position eccentric thereto, comprising a rotatable element having a plurality of adjustable actuating devices to cause such shifting.
8. In a knitting machine, the combination with the needles and the needle actuating mechanism, of additional-thread supplying means comprising a thread carrier, means to cause that thread delivery point
- of the carrier to revolve about the needles, including a rotating member, a cam block connected with the thread carrier and slidable in a slot in said rotating member, a 46
slidable bolt mounted concentric with the axis of said rotating member engaging said cam block, and automatic means to move said bolt.
9. In a knitting machine, the combination with the needles and the rotating cam ring of the needle actuating mechanism, additional-thread supplying means comprising a pivotally hung thread carrier, means 55 to cause the thread delivery point of the carrier to revolve about the needles, including a rotating member and a toothed wheel, a rod connected with and rotating with the cam ring, a rack bar mounted on said rod 60 and adapted to engage said toothed wheel, said rack bar moving with the rod when the latter revolves with the cam ring, and means to move the rack bar along the rod to change its operative position with reference to said wheel.
10. In a circular knitting machine, the combination with the needles, and the needle-actuating mechanism, of additional thread-supplying means comprising a jointed finger, a support for said finger suspending the same above the needles whereby the finger hangs pendent above the latter, and means situated above the finger for rotating the same to cause its lower end to carry a 70
thread about the needles, the joint in the finger being situated below the needle support and the needle-rotating means, wherebv the portion of the finger contiguous to the needle may be swung horizontally. 75
80

In testimony that we claim the foregoing we have hereunto set our hands.

EDWARD RICK.

WILLIAM G. STOLZ.
